In Guatemala March 22, 1949

16 Claims. (Cl. 194-7)

1

The present invention relates generally to electrically operated fare boxes which, in response to insertion of a coin of predetermined denomination actuate a coin counting register and issue a ticket receipt.

It is a broad object of the present invention to provide an improved electrically operated fare box.

It is a further broad object of the invention to provide an improved electrically operated fare box which, in response to insertion of a coin, actuates a register and issues a ticket receipt.

It is a further object of the invention to provide an electrically operated coin controlled fare box which is responsive in its operations to a plurality of coins simultaneously inserted in the machine, to operate a counting register once for each of the coins, and to issue a ticket receipt for each of the coins.

It is another object of the present invention to provide a device which, in response to the insertion of a coin, initiates a cycle of operations including ticket feed, ticket separation by means of a cutting operation, counting, and deposit of the coin in a suitable receptacle, after which the device is readied for a succeeding similar operation in response to a further coin, deposited simultaneously with the first coin, or at any time thereafter.

Another object of the invention resides in the provision of a coin controlled fare box which is reliable in operation and economical of construction, and which readily lends itself to maintenance.

The above and still further objects, features and advantages of the present invention will become apparent upon consideration of the following detailed description of a specific embodiment of the invention especially when taken in conjunction with the accompanying drawings where-
in:

Figure 1 is a plan view of a fare box in accordance with the present invention;

Figure 2 is an elevational side view of the structure of Figure 1, with chassis plates removed;

Figure 3 is a view of the structure of Figure 1 in front elevation;

Figure 4 is a view in rear elevation, corresponding generally with the structure illustrated in Figures 1 and 2; and

Figure 5 is an elevational view of a mechanical detail to the structure.

Briefly described the present invention is a coin operated device which is driven by an elec-

2

tric motor. The latter is energized in response to insertion of a coin into the apparatus, and when energized executes successive forward rotations and reverse rotations of predetermined extent. Energization of the motor occurs in response to insertion of the coin into the apparatus, by virtue of the fact that the coin when inserted bridges a pair of contacts which are in series with the motor and with a power supply line for the motor. In the course of a cycle of operations of the motor, consisting of one forward and one reverse rotation, the coin is released from between the contacts, terminating the cycle in the absence of a further coin in the coin chute. Should such a further coin have been deposited in the coin chute either simultaneously with the first coin, or during the cycle of operations, the second coin again bridges the contacts, and the motor executes a further cycle of operations. Should no further coins exist in the coin chute the motor becomes deenergized.

During forward rotation of the motor a ticket actuating drum is driven by the motor shaft through a uni-directional clutch mechanism for a distance sufficient to eject one ticket from the machine from a continuous strip of such tickets. On reverse motion of the motor the clutch slips, so that the ticket feeding drum is not actuated. However, on such reverse motion a knife blade actuating arm engages one of a pair of knife blades and drives the knife blades into shearing engagement. The ticket having been fed between the knife blades during the feeding operation on the forward rotation of the motor, is severed. As the moving knife blade reaches its top position it raises the arm of a ratchet type counter, and thereby registers or counts the operation. At the same time the moving knife blade actuates one of the contacts which are bridged by the coin in such sense as to separate the contacts and permit the coin to drop into a receptacle. The moving knife blade is then released, and very rapidly returns to its original position in response to force supplied by a spring, and in so doing releases the contacts so that they return to their original position in response to a bias spring.

Should two coins have been inserted in the coin chute simultaneously, the movement of the contacts will be sufficiently rapid to engage the second of the coins after dropping the first of the coins, so that the contacts will again be bridged and a further cycle of operations will occur. Should no further coin exist in the coin

chute the operation of the device will be terminated.

Referring now more specifically to the drawings the reference numeral 1 identifies an electric motor, which when energized executes forward and reverse motions of predetermined extent in succession until de-energized. Motors of this character are described in the U. S. Patents to H. R. Stuart, #1,821,123 issued September 1, 1931 and B. B. Holmes, #1,708,093 issued April 9, 1929. Electric motors of this type are well known in the art and accordingly, the details of the electric motor have not been illustrated and are not herein described. The electric motor 1 is supplied with a shaft 2, provided with a pulley 3. Secured to the pulley 3 is a pulley arm 4 which extends generally radially of the pulley 3, and which is so mounted with respect to the pulley 3 as to be rigid during reverse rotation of the electric motor 1, and to be resilient or to give during forward rotation of the electric motor 1. The desired properties of the pulley arm 4 may be accomplished in various known ways, the preferred way being illustrated in Figure 5 of the drawings, and described hereinafter. It is the function of the pulley arm 4, when actuated during reverse rotation of the electric motor 1, to raise a movable knife blade 5, which is pivotably mounted on a pin 6, against the counter force exerted by a coil spring 7, the knife blade 5 at the top of its stroke as seen in Figure 3, actuating the arm 8 of a conventional counter 9, to insert therein a single digit, and further entering into shearing engagement with a stationary knife blade 10, for cutting a ticket from a ticket roll or strip 11. After the moving knife blade 5 has reached the top of its stroke and accomplished its counter actuating and ticket cutting functions, the pulley arm 4 passes above the end of the knife blade 5 and out of engagement therewith, whereupon the spring 7 very rapidly returns the knife blade 5 to its initial position, as illustrated in Figure 3 of the drawings.

On forward rotation of the electric motor 1 the pulley arm 4 is driven into contact with the upper edge of the knife blade 5, as seen in Figure 3 of the drawings, and by reason of its resilience is enabled to ride over the knife blade 5, to a position adjacent its underside, as illustrated in Figure 3 of the drawings, in readiness for a ticket cutting operation.

Further secured to the motor shaft 2 is a ticket actuating drum 12, which is driven from the shaft 2 via a one way clutch on forward rotation of the motor 1. The one way clutch comprises a cam 13 which is rigidly secured to the shaft 2, and which rides in an axial aperture 14 provided in the drum 12. Additionally, the clutch comprises a pin 15, mounted in a radial aperture 16 in the drum 12 and extending into the axial aperture 14 by virtue of pressure exerted by a spring 17 located behind pin 15 in radial aperture 16. The pin 15 constitutes a driven member of a one way clutch, which is driven by the toothed cam 13, the latter operating as the driving member of the clutch.

A further toothed cam 18 is provided, which is secured to the feed drum 12 in any convenient fashion, and which cooperates with a resilient blocking lever 19, secured to a pin 20 at one end, and the other end of which rides on the cam 18 during forward rotation of the feed drum 12. The teeth of toothed cam 18 engage the other end of the locking lever 19 on reverse rotation of the shaft 2. Accordingly, on rearward rotation

of the shaft 2, which is clockwise as seen in Figure 2 of the accompanying drawings, the pin 15 rides on the cam surface of the toothed cam 13, while engagement of the arm 19 with a tooth of the cam 18 prevents rotation of the feed drum 12. On forward rotation, which is counter-clockwise as seen in Figure 2 of the drawings, a tooth of the toothed cam 13 engages the pin 15 and drives the feed drum 12, the end of the blocking arm 19 then riding on a cam surface of the locking cam 18.

The drum 12 is provided with a plurality of driving pins 21, which engage holes provided in the ticket strip 11, and which serve to actuate the ticket strip 11 to the left as seen in Figure 2, when the drum 12 rotates in a counter-clockwise direction on forward rotation of the motor 1.

The ticket strip 11 may be fed from a roll (not illustrated), and there are provided a number of guide rolls 23 and guide pins 24 for guiding the ticket strip to and over the drive drum 12 and thence to an opening in the machine adjacent knife blade 10, to which each ticket may be fed, and from which each ticket may be removed after it has been severed.

A coin chute 25 is provided, the side walls 26 of which may be fabricated of plastic or other insulating material, and at the edges of which may be provided a pair of contacts 27, 28, fabricated of superposed metal sheets, 27¹, 27², and 28¹, 28² respectively which are resilient in nature. The distance between the contacts is such that upon insertion of a coin into the coin chute the coin bridges the contacts 27, 28, completing an electrical circuit (not shown) for the electric motor 1. One of the contacts 27 is normally rigidly secured within the coin chute 25, while the other of the contacts 28, is secured to one arm 29 of a pivotably mounted bell crank lever 30, which is normally biased by means of a coil spring 31 into its position within the coin chute. The other arm 32 of the bell crank lever 30 is arranged to be engaged by an end of the moving knife 5, when the latter reaches its uppermost position, thus pivoting the bell crank about its pivot point in such sense that the contact 28 is separated sufficiently from the contact 27 to permit the coin to drop into a suitable receptacle.

It is precisely at this moment that the knife blade arm 5 is released by the pulley arm 4, and moves rapidly down, releasing the bell crank 30. The latter then is pivoted in response to its biasing coil spring 31 in such sense that the contact 28 is again thrust toward contact 27. The action takes place with sufficient rapidity that should several coins have been inserted in the coin chute during the ticket issuing and counting operation, one coin will be released by contacts 27, 28, but the next succeeding coin will be trapped thereby, and accordingly the circuit for the electric motor will be again completed and the latter will then proceed through a further cycle of operations in response to the second coin.

Parallel plates 33 and 34 form supports, for the mechanism of the present invention, between which are mounted the guide rolls 23 and the pins 24 which guide the paper strip 11, as well as the feed drum 12 and its associated one way clutch. Extending at right angles from the plate 34 is a bracket 35, to which is secured the pin 6, which supports the knife blades 5 and 10, and on which knife blade 5 pivots. Extending outwardly and at right angles to the plate 33 is a further bracket 36, to which is secured the register or counter 9, and the coin chute 25. The motor

shaft 2 extends between the plates 33 and 34, the motor 1 being mounted outside the plate 33.

Reference is made to Figure 5 of the accompanying drawings which illustrates certain details of the pulley arm 4, which is shown as consisting of two arm segments, 4a, 4b, one of which, 4a, is secured to the pulley 3, and the other of which, 4b is pivotably mounted on a pin 31, extending from segment 4a, and is urged by means of a coil spring 33 into colinearity with the arm segment 4a. The arm segment 4a is provided with a stop 39 which prevents counter-clockwise rotation of the arm segment 4b about the pin 31, when the arm segment 4b is colinear with the arm segment 4a. On the other hand clockwise rotation of the arm segment 4b about the pin 31 is not prevented, but takes place against the bias force exerted by the coil spring 33. Accordingly, on forward rotation of the motor shaft 2, the arm segments 4a and 4b rotate counter-clockwise, as seen in Figure 5, and when the arm segment 4b rests on the upper surface of the movable knife 5, the arm segment 4b pivots about the point 31 until the arm segment 4b slips over the top of the movable knife blade 5, and attains a position under the knife blade. On reverse rotation of the motor shaft 2 on the other hand, the arm segments 4a and 4b act as a rigid single member, by virtue of the stop 39 which prevents counter-clockwise rotation of the arm segment 4b about the pin 31. Accordingly, the arm 4 raises the movable knife blade 5 until such time as the outward end of the arm segment 4b slips from under the movable knife blade 5, the latter action taking place by reason of the fact that the end of the arm segment 4b describes an arc of a circle.

Describing now briefly the operation of the mechanisms and structures above described in detail, one or more coins may be inserted in the coin chute 25, the lowermost of the coins bridging the contacts 27 and 28, which have a normal separation such as to prevent passage of any coin. When the contacts are bridged an electric circuit is completed for an electric motor 1, which proceeds to execute forward and reverse rotations of predetermined extent so long as the circuit is energized. Upon forward rotation of the electric motor 1 a ticket feeding drum 12 is actuated, through a one way clutch comprising a toothed cam 13 secured to the shaft 2 of the electric motor 1 and a pin 15 secured to the ticket feeding drum 12, and extending into the path of the teeth of the tooth cam 13. The ticket feeding drum accordingly feeds a predetermined length of ticket to a cutting station immediately beneath a stationary knife blade 10.

On reverse rotation of the electric motor 1, the one way clutch which drives the ticket feeding drum 12 in response to forward rotation of the electric motor 1, slips, so that the ticket feeding drum 12 remains stationary. Positive means are provided to prevent reverse rotation of drum 12.

The pulley arm 4, which is located under the movable knife blade 5, raises the movable knife blade 5, on reverse rotation of the electric motor 1, until the knife blade 5 reaches shearing engagement with the stationary knife blade 10 and cuts off one ticket. On still further movement of the pulley arm 4 the latter is disengaged from the movable knife arm 5, and the latter, which is spring biased downwardly by means of a coil spring, rapidly returns to its original or unactuated condition.

Substantially simultaneously with the ticket cutting operation or slightly thereafter, the movable knife blade 5 actuates the bell crank 30, on which is mounted one of the coin holding contacts 28, and separates the coin holding contacts 27 and 28, permitting the coin to fall into a receptacle provided for that purpose. When the movable knife blade 5 is returned to its original position the bell crank 30 is rapidly returned to its original or unactuated position in response to bias provided by coil spring 31. This action takes place with sufficient rapidity so that should a plurality of coins have been inserted simultaneously in the coin chute 25, one of the coins will be dropped and the contacts 27, 28 turned to their unactuated or normal position, in time to retain the succeeding coin, thereby again completing a circuit for the electric motor 1, and enforcing a succeeding cycle of operations of the machine.

Due to the provision of the superposed resilient leaf contacts 27¹, 27², 28¹, 28², on the contact members 27, 28 respectively, it is insured that the metallic coin closes the motor circuit at all times. For, as will be apparent from an inspection of Figure 4 of the drawing, the coin when dropped in the chute will be contacted on each side thereof at two places by the ends of the resilient leaf contacts. Even if a poor contact exists at one spot—say adjacent member 27¹, by reason of the presence of rust, etc., on the coin, a good electrical contact is likely to be made at the other spot, i. e. when the member 27² touches the coin. Further, each coin, in descending to a position of rest on contact members 27, 28, is rubbed by the resilient leaf contacts, and thereby tends to be cleaned, so that a good electrical contact may be made therewith.

Primary reliance for establishing a circuit for the electric motor 1 is placed in contact between the coin and resilient leaf contacts 27¹, 27², 28¹, 28², and accordingly contact members 27, 28 may or may not be electrically conductive, as desired. Suitable insulating mountings must be utilized (not shown) for insulating the electrical contacts from the body of the machine, or if preferred, the body of the machine may be utilized as a ground for the electric motor 1, in which case only one set of the contacts need be insulatedly mounted, as will be clear to those skilled in the art.

It will be noted that utilization of a reversing motor, which executes periodic forward and reverse rotations, or which drives a shaft in predetermined forward and reverse rotations, results in simplification of apparatus of the character herein described. The severance of a ticket, for example, may be arranged to take place at any time during reverse rotation, and the release of a coin from the coin chute may likewise take place at any time during reverse rotation following ticket severance and registration or counting. Should a reverse rotation of motor shaft 2 not have been completed when a coin is released this will prove of no importance, since completion will take place in response to a succeeding coin, and thereafter a further cycle of operations will take place, of ticket feed, registration, ticket severance, and coin release. The timing cycle is, accordingly, by no means critical, and overrunning of the electric motor, after its energizing circuit has been broken, of no effect.

While we have described one specific embodiment of the invention, variations of structure and detailed arrangement of parts may be resorted to

without departing from the true spirit and scope of the invention as defined in the appended claims.

What we claim and desire to secure by Letters Patent of the United States is:

1. In combination in a coin operated electric motor actuated fare box, wherein said electric motor when energized executes successive forward and reverse rotations, a coin chute, a pair of contacts located in said coin chute in position to be bridged by a coin in said chute, at least one of said contacts being movable from said coin chute, an electric energizing circuit for said electric motor including said contacts in series, a ticket strip, means responsive to a forward rotation of said motor for feeding a predetermined length of said ticket strip to a cutting position, a pair of cutting knives at said cutting position, one of said cutting knives being stationary on one side of said ticket strip and the other of said cutting knives being on the other side of said ticket strip and being movable from an idle position to a position in shearing engagement with said stationary cutting knife, spring means normally biasing said other of said cutting knives to said idle position, actuating means responsive to predetermined reverse rotation of said electric motor to actuate said other of said cutting knives to said position in shearing engagement, means responsive to said other of said cutting knives in said last named position for actuating said at least one of said contacts from said coin chute, said actuating means in response to further reverse rotation of said electric motor releasing said other of said cutting knives for actuation in response to said spring means.

2. In a coin controlled mechanism for issuing a ticket from a strip of tickets in response to each of a plurality of coins inserted in a coin chute, an electric motor having a shaft rotatable in successive forward and reverse rotations of predetermined extent during energization of said electric motor, holding means normally blocking said coin chute, means actuated by said shaft only in response to each of said reverse rotations for rapidly actuating said holding means to unblock said coin chute to release one coin and then rapidly to again block said coin chute, means responsive only to presence of a coin in a predetermined position in said coin chute for energizing said motor, means for feeding a predetermined length of said strip to a severing station in response to each of said forward rotations, and means for severing a ticket from said strip at said severing station in response to each of said reverse rotations and prior to actuation of said holding means to unblock said coin chute.

3. In a coin controlled mechanism for issuing a ticket from a strip of tickets in response to each of a plurality of coins inserted in a coin chute, an electric motor having a shaft rotatable in successive forward and reverse rotations of predetermined extent during energization of said electric motor, a device for blocking said coin chute to passage of coins at a predetermined location therein, in one position of said device, and for unblocking said coin chute in another position of said device, means for energizing said electric motor only in response to occupation by one of said coins of said predetermined location, means responsive to each forward rotation of said shaft for feeding a predetermined length of said strip to a severing station, means responsive to each reverse rotation of said shaft for severing one of said tickets at said severing station and for rapid-

ly actuating said device to said another position and thereafter to said one position.

4. In a coin controlled mechanism for issuing a ticket from a strip of tickets in response to each of a plurality of coins simultaneously inserted in a coin chute, an electric motor having a shaft rotatable in successive forward and reverse rotations of predetermined extent during energization of said electric motor, a ticket feeding drum for feeding said strip of tickets to a severing station, means for actuating said ticket feeding drum only in response to each of said forward rotations, a pair of co-acting knife blades for severing said tickets from said strip of tickets, means for actuating said pair of co-acting knife blades to sever one of said tickets from said strip only in response to reverse rotation of said shaft, a pair of coin holding members in said coin chute, said coin holding members having a normal separation smaller than the diameter of one of said coins for retaining said coins in said coin chute during normal separation, an electric circuit for energizing said electric motor, said electric circuit being closed in response to one of said coins only while said one of said coins is retained in said coin chute by said coin holding members, means operative in response to each reverse rotation of said shaft and in synchronism with severance of a ticket for actuating said coin holding members to sufficient separation to release said one of said coins and thereafter to said normal separation.

5. In a coin controlled mechanism for issuing a ticket from a strip of tickets in response to each of a plurality of coins simultaneously inserted in a coin passageway, an electric motor having a shaft rotatable in successive forward and reverse rotations of predetermined extent during energization of said electric motor, a ticket feeding means for feeding a predetermined length of said strip in response to each operation of said ticket feeding means, means for actuating said ticket feeding means only in response to each of said forward rotations, a pair of co-acting knife blades for severing said tickets from said strip at a severing station, means for actuating said pair of co-acting knife blades to sever one of said tickets from said strip only in response to reverse rotation of said shaft, a pair of coin retaining members in said passageway, said coin retaining members having a normal separation smaller than the diameter of one of said coins for retaining said coins in said passageway, means for rapidly separating said coin retaining members sufficiently to release one of said coins, an electric circuit for energizing said electric motor, means responsive to retention of one of said coins in said passageway by said coin retaining members for completing said electric circuit, resilient means normally urging said coin retaining members to said normal separation, means operative only in response to reverse rotation of said shaft and synchronized with severance of a ticket for rapidly actuating and then releasing said means for rapidly separating said coin retaining members.

6. In a coin controlled mechanism for issuing a ticket from a strip of tickets in response to each of a plurality of coins simultaneously inserted in a coin chute, an electric motor having a shaft rotatable in successive forward and reverse rotations of predetermined extent in response to energization of said electric motor, ticket feed means for feeding a predetermined length of said strip to a severing station, means for actuating said ticket feed means only in response to said forward

rotations, means operative only in response to each of said reverse rotations for severing a ticket from said strip at said severing station, holding means in normal condition retaining said plurality of coins in said coin chute and operable when actuated for releasing only a first one of said coins, an electric circuit for energizing said electric motor, means for completing said electric circuit only in response to the presence of at least one coin in said coin chute, means operable only in response to each reverse rotation of said shaft and synchronized with severance of a ticket for rapidly actuating said holding means to release said first one of said coins and to return to said normal condition in time to hold a succeeding one of said coins.

7. The combination in accordance with claim 6 wherein said means operable only in response to each reverse rotation of said shaft for rapidly actuating said holding means comprises said means for severing.

8. In a coin controlled mechanism for issuing a ticket from a strip of tickets in response to each of a plurality of coins simultaneously inserted in a coin passageway, an electric motor having a shaft rotatable in successive forward and reverse rotations of predetermined extent during energization of said electric motor, a ticket feeding drum, means comprising a one way clutch driven from said shaft for actuating said ticket feeding drum for feeding one ticket only to a severing station only in response to each of said forward rotations, a pair of co-acting knife blades for severing said tickets from said strip at said severing station, means operative only in response to each of said reverse rotations for actuating said pair of co-acting knife blades to sever one of said tickets from said strip, a pair of electric contacts in said passageway, said contacts having a normal separation smaller than the diameter of one of said coins for retaining said coins in said passageway, actuating means for rapidly separating said contacts to release one of said coins, an electric circuit for energizing said electric motor including said contacts and said coin in series, resilient means urging said contacts to said normal separation, and means driven by said shaft and operative only in response to reverse rotation of said shaft and in synchronism with the severance of a ticket for actuating and then releasing said actuating means, for rapidly separating said contacts and then restoring said normal separation of said contacts.

9. In a coin controlled mechanism for issuing a ticket from a strip of tickets in response to each of a plurality of coins, an electric motor, a shaft, means comprising said electric motor for driving said shaft in successive forward and reverse rotations each of predetermined extent, a ticket feeding drum, a one way clutch coupling said shaft and said ticket feeding drum in driving relation only in response to forward rotation of said shaft, a pair of co-acting knife blades for severing tickets from said strip of tickets, means for actuating said pair of co-acting knife blades for severing tickets from said strip of tickets only in response to reverse rotation of said shaft, a pair of contacts arranged to hold one of said coins when in one condition and to release said one of said coins when in another condition, said pair of contacts normally in said one condition, an electric circuit for energizing said electric motor, said electric circuit including said contacts and said one of said coins in series, whereby release of said one of said coins breaks said

5 10 electric circuit and effects de-energization of said electric motor, and means for actuating said pair of contacts to said another condition in response to rotation of said shaft and in synchronism with said severing.

10. In a coin controlled mechanism for issuing a ticket from a strip of tickets in response to each of a plurality of coins, an electric motor having a shaft rotatable in successive forward and reverse rotations of predetermined extent during energization of said electric motor, a ticket feeding drum, means comprising a one way clutch for actuating said ticket feeding drum for feeding a ticket only in response to each of said forward rotations, a pair of co-acting knife blades for severing said tickets from said strip of tickets, means responsive only to each reverse rotation of said shaft for actuating said pair of co-acting knife blades to sever one of said tickets from said strip, a passageway for said coins, a pair of electric contacts in said passageway, said electric contacts having a normal separation smaller than the diameter of one of said coins, for retaining said coins in said passageway, 20 means for rapidly separating said contacts to release one of said coins, an electric circuit for energizing said electric motor and including said electric contacts and one of said coins in series, resilient means normally urging said electric contacts to said normal separation, means operative in response to each reverse rotation of said shaft and synchronized with severance of a ticket for actuating and then releasing said means for rapidly separating said contacts, whereby said contacts return to said normal separation in response to said resilient means.

11. In a coin controlled mechanism for issuing a ticket from a strip of tickets in response to each of a plurality of coins simultaneously inserted in a coin passageway, an electric motor having a shaft rotatable in successive forward and reverse rotations of predetermined extent during energization of said electric motor, a ticket feeding drum, means comprising a one way clutch for actuating said ticket feeding drum for feeding a ticket only in response to each of said forward rotations, a pair of co-acting knife blades for severing said tickets from said strip of tickets, means operative only in response to each of said reverse rotations for actuating said pair of co-acting knife blades to sever one of said tickets from said strip, a pair of electric contacts in said passageway, said contacts having a normal separation smaller than the diameter of one of said coins for retaining said coins in said passageway, means for rapidly separating said contacts to release one of said coins, an electric circuit for energizing said electric motor including said contacts and one of said coins in series, resilient means urging said contacts to said normal separation, means operative in response to each reverse rotation of said shaft and synchronized with severance of a ticket for transiently actuating and then releasing said means for rapidly separating said contacts, whereby said contacts are separated to release one of said coins and return to said normal separation in response to said resilient means, retaining succeeding coins in said coin chute.

12. The combination in accordance with claim 1 wherein each of said pair of contacts comprises at least two electrically conductive resilient leaf members located in superposition in said chute.

13. The combination in accordance with claim 1 wherein each of said pair of contacts comprises

at least two discrete vertically separated resilient leaf members, each of said leaf members having only an end portion extending into the path of a coin in said coin chute.

14. The combination in accordance with claim 5, wherein said means responsive to retention of one of said coins in said passageway for completing said electric circuit comprises at least two electrically conductive resilient vertically superposed leaf contact members located in said coin chute on each side of the path of said coin, for bridging by said coin. 5

15. The combination in accordance with claim 11, wherein each of said contacts is supplemented by at least one further resilient leaf contact member connected thereto, and having a free end extending in the path of a coin, and in vertical superposition of one of said contacts, the weight of a coin being sufficient to overcome the resilience of said resilient leaf contact member. 15

16. The combination in accordance with claim 10, wherein each of said contacts includes at least two vertically superposed resilient electrically 20

conductive leaf members, positioned and spaced for bridging by one of said coins while said one of said coins is retained in said passageway.
